UNITED STATES PATENT OFFICE.

FRANKLIN P. PAYNE, OF PORT JEFFERSON, NEW YORK.

APPARATUS FOR APPLYING CEMENT.

No. 866,511.

Specification of Letters Patent.

Patented Sept. 17, 1907.

Application filed March 13, 1907. Serial No. 362,194.

To all whom it may concern:

Be it known that I, FRANKLIN P. PAYNE, a citizen of the United States, residing at Port Jefferson, in the county of Suffolk and State of New York, have invented 5 certain new and useful Improvements in Apparatus for Applying Cement, of which the following is a specification, reference being had therein to the accompanying drawing.

My invention relates to improvements in apparatus 10 or devices for filling the corrugations of sheet metal ceilings or the like, with cement or other plastic material.

The object of the invention is to provide a simple and practical means whereby the cavities of corrugated 15 sheet metal ceilings may be quickly and effectively filled with cement, or the like, at a comparatively small expenditure of labor.

With the above and other objects in view, the invention consists in the novel features of construction, combination and arrangement of parts hereinafter fully described and claimed, and illustrated in the accompanying drawings, in which

Figure 1 is a vertical section through the apparatus showing it in use for filling a corrugated sheet metal 25 ceiling or roof; Figs. 2 and 3 are detail vertical sections, on an enlarged scale, taken respectively on the planes indicated by the lines 2-2 and 3-3 in Fig. 1; Fig. 4 is a perspective view of one end of the combined support and guide; Fig. 5 is a perspective view of one end of the 30 cement trough or holder; Fig. 6 is a perspective view of one of the supports for the cement holder; and Fig. 7 is a detail sectional view through the carriage which carries the plunger for pressing the cement from its holder and into the corrugations of the ceiling or roof.

35 The present embodiment of my invention is especially designed for filling the corrugations of a corrugated sheet metal ceiling or roof such as illustrated in Figs. 1, 2 and 3 of the drawings. This ceiling is composed of a plurality of sheet metal plates A formed with longitudinal 40 corrugations B and having their ends resting or supported upon and secured to the top flanges of parallel I-beams C. The form of the apparatus shown is also adapted to fill but one of the corrugations B at a time and it comprises a longitudinal bar 1 which forms 45 a support for a cement holder or trough 2 and also a track for a carriage 3 which carries a plunger or pressing head for forcing the cement from the holder 2 into the corrugations B. The support 1 is preferably of rectangular form and of such length that it will fit between 50 the I-beams C and be supported at its ends by the horizontal lower flanges of the same. At suitable points intermediate its ends are formed vertical sockets 4 for the cylindrical lower ends of pivots 5 of the upright rods 6 which have at their upper ends right angularly 55 projecting arms 7 for supporting the trough or holder 2.

The upright supports 6 are preferably arranged in pairs and since their lower ends are pivotally mounted their upper ends or arms 7 may be swung under the trough 2 for the purpose of supporting the same against the bottom of the ceiling or roof A, as clearly shown in Fig. 2. In the top of the bar or support 1 is formed a longitudinally extending groove or channel 8 which forms a track or guideway for a roller 9 journaled at 10 in a casing 11 forming the lower portion of the carriage 65 3. This casing has its upper end enlarged, as shown in Fig. 7, so as to protect the roller 9 and in its top is arranged a nut 12 for the reception of the threaded lower end 13 of a rod or bar 14 adapted to serve as a handle for manipulating the carriage or device 3. 70 Upon the upper end of the handle 4 is provided a head or enlargement 15 adapted to serve as a plunger or pressing block which co-acts with the cement holder 2. The head 15 is of substantially rectangular form and has its top longitudinally curved so that it may be readily 75 pressed against the bottom of the holder 2 and moved along the same. The cement holder 2 is preferably in the form of a trough of substantially semi-circular shape in cross section and it is constructed of resilient perforated sheet metal so that it may be flattened to 80 cause the cement which it contains to be forced into one of the corrugations B.

The operation of the invention is as follows: The supporting and track bar 1 is first placed in position upon the lower flanges of the I-beams C directly beneath 85 one of the corrugations B in the ceiling or roof A; the trough or holder 2 is then filled with cement or any other plastic material and placed upon the inwardly projecting arms 7 of the upright supports 6. The latter hold said trough in a horizontal position beneath 90 the corrugation B with its beaded edges in contact with the bottom face of the ceiling. The carriage 3 is then placed between the track or support 1 and the holder 2 with its roller 9 in the guide groove 8 and its pressing head or block 15 in engagement with the bottom of the holder. The operator who grasps the handle 14 of the carriage in his hand, as shown in Fig. 1, then straightens said rod so that the portion of the holder engaged by the block or head 15 will be flattened so as to force the cement into the corrugation B, as will 100 be readily seen upon reference to the first three figures of the drawings. When in this vertical position the carriage is moved longitudinally between the bar 1 and holder 2 so that the corrugation will be completely filled from end to end. Owing to the threaded connection 13 between the handle 14 and the roller casing 11 the length of the carriage may be varied so that the cement holder will be flattened or collapsed to the extent necessary to effectively force the cement into the corrugation. After one corrugation has been filled the 110 bar 1 is moved beneath the next one and the above described operation is repeated.

While I have shown the invention as adapted for filling one corrugation at a time, it will be understood that any number may be simultaneously filled and that the invention may be adapted for operating upon corrugated ceilings or the like of any description.

Having thus described my invention what I claim and desire to secure by Letters Patent is:

1. The combination of a collapsible holder for plastic material, means for supporting said holder and means for collapsing said holder, substantially as and for the purpose set forth. 10
2. The combination of a resilient holder for plastic material, means for supporting said holder and means for collapsing said holder, for the purpose set forth. 15
3. The combination of a collapsible holder for plastic material, means for supporting said holder, a guide and a pressing device to travel between said guide and said holder, for the purpose set forth. 20
4. The combination of a collapsible holder for plastic material, means for supporting said holder, a guide, a pressing device to travel between said guide and said holder and means for adjusting said pressing device, for the purpose set forth. 25
5. The combination of a collapsible holder for plastic material, means for supporting said holder and a pressing device to engage and collapse said holder, for the purpose set forth. 30
6. The combination of a collapsible holder for plastic material, a guide, means on said guide for supporting said holder, and a pressing device to travel between said guide and said holder, for the purpose set forth. 35
7. The combination of a resilient holder for plastic material, a guide bar, means upon said bar for supporting said holder and a pressing device to travel between said bar and said holder, for the purpose set forth. 40
8. The combination of a resilient holder for plastic material, means for supporting said holder, a grooved guide bar and a pressing device to collapse said holder and adapted to travel in the groove of said guide bar. 45

9. The combination of a resilient holder for plastic material, means for supporting said holder, a guide, a carriage to travel upon said guide and a pressing head carried by said carriage to engage and collapse said holder. 50

10. The combination of a resilient holder for plastic material, means for supporting said holder, a grooved guide bar, a longitudinally extensible pressing device having a head at one end to engage and collapse said holder and a roller upon the other end of said device to engage and run in the groove in said bar. 55

11. The combination of a resilient holder for plastic material, a support, swinging uprights upon the latter having portions to engage and support said holder and a pressing device to collapse said holder. 60

12. The combination of a resilient trough like holder for plastic material, means for holding the same against the element to which the contents of said holder is to be applied and a pressing device to collapse said holder. 65

13. The combination of a trough like holder for plastic material, means for supporting said holder, constructed of perforated resilient sheet material and means for collapsing said holder. 70

14. The combination of a collapsible holder for plastic material, means for supporting said holder, a guide and a pressing device to travel between said guide and said holder, said device consisting of two sections having an adjustable screw threaded connection. 75

15. The combination of a collapsible holder for plastic material, means for supporting said holder, a guide and a pressing device to travel between said guide and said holder, said device consisting of a hand rod having a pressing head at one end and a threaded portion at its other end, a recessed body formed with a threaded opening to receive the threaded end of said rod and a roller journaled in the recess of said body. 80

In testimony whereof I hereunto affix my signature in presence of two witnesses.

FRANKLIN P. PAYNE.
